UNITED STATES PATENT OFFICE.

EDWARD S. BRADFORD, JR., OF CHICOPEE, MASSACHUSETTS, AND MAURITZ OLSON, OF BRIDGEPORT, CONNECTICUT; SAID OLSON ASSIGNOR TO SAID BRADFORD.

POWER-HACKSAW.

1,004,651.

Specification of Letters Patent.

Patented Oct. 3, 1911.

Original application filed September 24, 1909, Serial No. 519,371. Divided and this application filed June 17, 1910. Serial No. 567,532.

To all whom it may concern:

Be it known that we, (1) EDWARD S. BRADFORD, Jr., and (2) MAURITZ OLSON, citizens of the United States, residing at (1) 5 Chicopee, county of Hampden, State of Massachusetts, and (2) Bridgeport, county of Fairfield, State of Connecticut, have invented an Improvement in Power-Hacksaws, of which the following is a specification.

10 This invention relates to certain new and useful improvements in power hack saws, being a division of our pending application for patent filed Sept. 24, 1909, Serial No. 519,371.

15 The invention has for its object the provision of improved means for lifting the saw during its return stroke in order to prevent dragging of the teeth upon the work.

20 A further object is to provide means for varying the distance to which the saw is raised during the return stroke.

The invention will be hereinafter fully set forth and particularly pointed out in the claims.

25 In the accompanying drawings:—Figure 1 is a plan view of a power hack saw embodying our improvements. Fig. 2 is a side elevation thereof. Fig. 3 is an end view looking from the right in Fig. 2. Fig. 4 is 30 an enlarged view in side elevation, corresponding to Fig. 2, parts being broken away and showing a changed position of the blade lifting mechanism. Fig. 5 is a detail rear elevation corresponding with Fig 4. Fig. 6 35 is a section on the line 6—6 Fig. 5.

Referring to the drawings, 10 designates a frame provided with bearings 11 supporting a shaft 12 on which is mounted a driving pulley 13 which receives power from any 40 suitable source. Mounted to rotate on a shaft 14 is a sleeve 15 provided with a gear wheel 16 adapted to mesh with a pinion 17 carried by the shaft 12. The sleeve 15 is also provided with a cam 18 which lies in 45 the inner face of the gear wheel 16, and may be formed integral therewith if desired, (see Figs. 4 and 5). Upon the outer face of the gear wheel 16 is a slide 19 adapted to reciprocate in ways 20, and provided with a pin 50 21. Said pin is adapted to operatively engage an operating lever 22 pivotally supported in the frame at 23 and having its free end connected with the saw frame 24 by means of a link 25. The saw frame 24

is slidably mounted upon a bar 26 and is 55 provided with the usual saw blade 27. The slide 19 may be reciprocated in any suitable manner and the pin 21 may be connected with the operating lever 22 in any preferred way. The method illustrated in our pending application, above identified will be found both convenient and effective, and need not be further described here. Any suitable means for clamping the work may be employed, the device illustrated comprising relatively adjustable jaws 28.

The bar 26 is rigidly secured at one end to a disk 30 which is in turn secured to a shaft 31 journaled in suitable bearings 32 upon the frame work. The inner face of 70 the disk 30 is provided with a recess 33 in which is located an outwardly acting or expanding clamping ring 34, adapted to bear against the wall of the recess, bolts 35 being provided to prevent displacement of 75 said ring. The ends of the clamping ring 34 overlap, the inner end being specifically designated by 36 and the outer end by 36^a. Said ends are each pivotally connected to one end of an arm 37, as indicated at 38 80 and 38^a, and the lower end of said arm is provided with a roller 39 which bears on the face of the cam 18. A spring 40 connected to the arm 37 and to the frame work acts to retain the roller closely in engagement with 85 the face of the cam.

The operation is as follows:—The parts are so timed that at the end of the forward stroke of the saw, the roller 39 will ride up on the high portion of cam 18, the effect of 90 which is to swing the arm 37. Owing to the distance between the pivotal points of said arm to the spring clamping ring, said ring is expanded or forced outward, and caused to grip the wall of the recess 33, locking the 95 ring to the disk and oscillating the latter. The oscillation of the disk 30 swings the arm 26 which carries the saw upward, and retains it in the raised position during the return stroke, at the end of which the roller 100 will ride down onto the low portion of the cam, releasing the grip of the spring clamping ring upon the disk 30, and permitting said disk, the bar 26, and the saw to drop to their normal positions an instant before the 105 commencement of the next forward or operative stroke. The distance to which the saw is raised during the return stroke is deter-

mined by adjustment of the tension of the clamping ring 34. This adjustment is effected by means of a screw 41, mounted in the frame work and bearing against the upper end of the arm 37. It will be obvious that by tightening up said screw, the grip of the ring 34 upon the wall of the retaining recess 33 will be reduced, and consequently less oscillation will be imparted to the disk 30 by the movement of arm 37 and bar 26 upon which the saw frame reciprocates will not be swung as high. A slight loosening of the screw 41 will increase the grip of the clamping ring 34 upon the wall of the recess 33, thereby increasing the oscillation of the disk 30 and the lift of the saw carrying bar 26.

Having thus explained the nature of our invention, and described an operative manner of constructing and using the same, although without attempting to set forth all of the forms in which it may be made, or all of the forms of its use, what we claim is:—

1. An improvement in hack saws comprising a supporting bar, a disk to which one end of said bar is secured, said disk being provided with a recess, a saw mounted to reciprocate on said bar, a spring clutch ring mounted in said recess and adapted to engage the wall thereof, an operating arm for said clutch ring, and means for periodically actuating said arm, whereby the disk is oscillated to raise the bar upon the return stroke of the saw, and means for varying the period of engagement of said clutch ring and disk.

2. An improvement in hack saws comprising a supporting bar, a disk to which one end of said bar is secured, said disk having a recess, a saw mounted to reciprocate on said bar, a resilient clutch ring mounted in said recess and adapted to engage the wall thereof, an arm to which each end of said clutch ring is secured, said arm being provided with a beveled portion, means for pe-

riodically operating said arm to operate the clutch, whereby the disk is oscillated to raise the bar upon the return stroke of the saw, and means engaging the beveled portion of said arm for varying the period of engagement of said clutch.

3. An improvement in hack saws comprising a supporting bar, a disk to which one end of said bar is secured, said disk having a recess, a saw mounted to reciprocate on said bar, a resilient clutch ring mounted in said recess and adapted to engage the wall thereof, said ring being provided with overlapping ends turned in at an angle with relation to the body thereof, an operating arm having a beveled end and pivotally connected with both of said ends, a cam for actuating said arm, and an adjusting screw arranged to engage the beveled end of said arm.

4. An improvement in hack saws comprising a supporting bar, a disk to which one end of said bar is secured, said disk having a recess, a saw mounted to reciprocate on said bar, a resilient clutch ring mounted in said recess and adapted to engage the wall thereof, an adjusting screw for varying the period of engagement of said clutch ring with said disk, and means for periodically operating said clutch, whereby the disk is oscillated to raise the bar upon the return stroke of the saw.

In testimony whereof we affix our signatures in presence of the witnesses.

EDWARD S. BRADFORD, JR.
MAURITZ OLSON.
